STORAGE GARAGE

Montague Moore, Burnaby, British Columbia,
Canada

Application February 9, 1937, Serial No. 124,833

6 Claims. (Cl. 20—1.13)

My invention relates to improvements in storage garages, which are particularly adapted for short time parking of cars.

The objects of the invention are to provide a garage structure where all aisles and ramps have sufficient head room for trucks and high vehicles; to provide a ramp system whereby all vehicles after leaving the receiving floor travel in the same direction, both on going up to their parking stall and in travelling therefrom back to the receiving floor or exit. Further objects are to provide a garage whereby different areas are given different classification, such for instance as red, yellow, blue and green and cars to be parked are assigned to any of the colour areas and that a car assigned to any colour area in passing to or from its stall cannot travel on any ramp or aisle occupied by a car assigned to another colour area. A further object is to provide means where relatively little double parking is resorted to to make economical use of the floor space.

The invention consists essentially of a garage having superimposed floors separated by intermediate floors of lesser area and a plurality of sets of ramps in which each set serves separate floor areas from the areas served by any other of the sets of ramps, as will be more fully described in the following specification and shown in the accompanying drawings, in which:—

Fig. 1 is a plan view of the main or receiving floor of the building.

Fig. 2 is a plan view of the uppermost floor.

Figs. 3, 4, 5 and 6 are profile views each showing a separate ramp system and the floor areas served by said ramp system. The profiles are projected charts taken along the lines A—B—A of Figures 1 and 2.

Fig. 7 is a sectional view taken on the line 7—7 of Figure 1.

In the drawings like characters of reference indicate corresponding parts in each figure.

For the purpose of description, the use of colours or their index letters such as red or R, blue or B, yellow or Y and green or G will be made in reference to ramps, aisles and parking zones in order that the direction of travel of vehicles through the building will be more readily understood.

The building shown consists of an arrangement of alternate floors referred to as full floors and intermediate floors, all of which are above the main or receiving floor, though it will be obvious that a similar arrangement of floors may be provided below the receiving floor without

increasing the number of columns of superimposed ramps required to serve the several floors.

It is assumed for purpose of description that the plans shown in Figures 1 and 2 are set with that portion adjacent the top of the sheet as 5 being the north.

The building consists of a receiving floor 1 and upper floors 2, 3, 4, 5, 6, 7, 8 and 9, of which 3, 5, 7 and 9 are full floors and 2, 4, 6 and 8 are intermediate floors. The building is bounded by 10 a north wall 10, a south wall 11, an east wall 12 and a west wall 13.

In a building having eight floors, such as shown, eight vertical columns of ramps are provided, which are numbered respectively 14A, 15 14B, 14C, 14D, 14E, 14F, 14G and 14H, each of which consists of a plurality of up ramps 15 and down ramps 16 along which all traffic flows in the same direction, viz: up to the left and down to the right, the travel being always to the east 20 along the south end of the building and to the west along the north end of the building. Since there are eight upper floors including the full and the intermediate floors, there will be four up ramps 15 leading from the receiving floor 1 25 to the floors above and there will also be four down ramps 16 leading from the floors above to the receiving floor.

Each of the full floors 3, 5, 7 and 9 are provided with outside connecting traffic aisles 17E 30 and 17W, a centre connecting traffic aisle 18 and intermediate connecting traffic aisles 19E and 19W.

The intermediate floors 2, 4, 6 and 8 consist of two areas defined by the letters E and W following the numeral allotted to the respective floors, such as the intermediate floor 2 would consist of areas 2E and 2W. The intermediate floor areas are each provided with a single connecting traffic aisle 20, see Figures 3, 4, 5, 6 and 40 7, which aisles are immediately above or below one of the intermediate aisles 19E or 19W.

The floor areas on the full floors between the walls 12 and 13 and the outer aisles 17E and 17W respectively represent single parking spaces 45 21, and the areas between adjacent aisles constitute parking spaces 22, which are the length of two cars each, but since they are each accessible from both ends they too may be used for single parking and may be deemed single 50 parking spaces.

The floor areas on the intermediate floors 2, 4, 6 and 8 are each of two car length and therefore constitute double parking spaces which are indicated by the numeral 23. 55

The several parking areas will be divided and will be hereinafter referred to by colour such as red, blue, yellow and green and will be indicated on the drawings by the index letter of the respective colours such as R, B, Y and G.

5 Cars enter and leave the building from the receiving floor 1 and are tagged with a tag of the colour corresponding to one of the areas in which they are to be parked. If a rush develops 10 cars may be temporarily left on the receiving floor until the attendants have time to run them to their respective stalls.

15 Each profile view is taken as a line extending in the direction of travel of the cars in moving from the receiving floor up to any floor served by the particular starting up ramp and from the assigned parking space down again to the receiving floor. The up ramps are shown in full line and the down ramps in dotted line. The left 20 half of the profile view represents the ramp profile of the south half of the building and the right half of profile view represents the ramp profile of the north half of the building, so that the horizontal length of a profile view represents 25 a complete contour of a ramp system of the building.

30 It will be noticed that the up ramps in the ramp columns at one end, to wit, the south are inside or towards the centre of the building and the up ramps on the other end or north are outside or are remote from the centre of the building, the reason being that all cars arrive at their 35 parking floors from an up ramp and depart from their parking floors on a down ramp to which they have access without crossing any landing or other area traversed by other cars descending from their respective parking areas. By this arrangement no car in entering or leaving any floor above the receiving floor will cross any ramp or 40 area which another car may be travelling along.

45 In parking a car assigned to a red area, the car will leave the receiving floor at the inside up ramp 15 in the ramp column 14A and will proceed to any of the areas, indicated by heavy horizontal line in Figure 3 or any of the floors 2, 3, 4, 5 and 9, where it may turn in and park, for instance it may turn left at the top of the first ramp onto intermediate floor 2W and pass along its aisle 50 20 to its stall. On leaving it would back out of its stall and continue along the aisle 20 towards the north end of the building and turn left again onto the down ramp 16, shown in dotted line in Figure 3, which is in the ramp column 14H. This down ramp is inside and can only be occupied by 55 Red cars from upper Red areas. Another Red car may proceed upwards from the receiving floor, along the up ramp 15 in column 14A to a single parking strip on both sides of the centre aisle 18 of floor 3, if on the other hand a car is assigned to the floor 9 it would continue upwards along the up ramps of ramp columns 14A, 14B, 14C and 14D to the east side of the building, thence along the aisle 17E of floor 5, thence up on the same up ramps of ramp columns 14E, 14F, 60 14G and 14H and would land on floor 9 at the aisle 17W from whence it would be driven to its stall. This car in descending would run onto down ramps 16 in column 14A and would pass 65 progressively downwards on the outside down ramps through columns 14A to 14H from which it would land on the receiving floor facing west.

70 Cars assigned to blue areas leave the receiving floor on the up ramp 15 of column 14G and reach their first parking area on aisle 17W of floor 3, 75 see Figure 4, the descent from this area is from

the south end of aisle 19W reaching the receiving floor on down ramp 16 of column 14B. Alternately the "blue" cars may proceed upwards to any of floors 4, 5, 6 and 7 and return from any of these floors on ramps set aside entirely for 5 "blue" cars, all cars as before travelling in the same direction and without any interference from cars assigned to any other colour. In Figure 4 showing the floor areas assigned to "blue" 10 it will be noticed that the ramps do not extend upwards beyond floor 7 but the ramps could, if desired, be carried beyond this point to provide for rerouting of cars from the blue areas to another ramp series in the event of an accidental traffic block on any of the ramps of the blue ramp 15 system.

Figure 5 shows the travel and parking areas assigned to "green". The cars in this case start to rise from the receiving floor 1 in the north-east portion of the building on ramp 15 of the 20 ramp column 14E and reach their first parking on aisle 17W of floor 5 from whence upward travel continues to intermediate floor 6W, floor 7, intermediate floor 8E and the eastern portion of floor 9. In descending, "green" cars reach the receiving 25 floor in ramp column 14D.

Figure 6 shows the travel of cars assigned to "yellow". The cars leave the receiving floor at the ramp column 14C and may enter intermediate floor 2E at the aisle 20 or may enter floor 3, 30 floor 7, the intermediate floor 8W and floor 9 at the centre aisle 18. Cars assigned to yellow would in descending reach the receiving floor in ramp column 14F.

The building would be provided with suitable 35 entrance and exit openings 24 to the receiving floor 1.

On certain floors where double parking is provided, two or more stalls may be set aside for aisles as at 25, so as to afford passage way from 40 one colour area to another in case of traffic breakdown or to convert otherwise double parking spaces into single parking spaces. It will be obvious that cars could be rerouted over other floors in case of accident on any ramp, if necessary, but that so long as they pass to or from the areas to which they are assigned, as shown in the profiles shown in Figures 3, 4, 5 and 6, that no car of one colour denomination can pass a car of another colour denomination on any ramp or 50 aisle.

55 What I claim as my invention is:

1. A storage building having a receiving floor and superimposed floors designated alternately full floors and intermediate floors, each of said intermediate floors being divided into two areas of lesser total area than the adjacent full floors, a plurality of up ramps extending upwards to communicate with the superimposed floors and a plurality of corresponding down ramps connecting the superimposed floors with the receiving floor, each of said ramps being arranged to serve one only of the divided two areas of the intermediate floors the last mentioned up and down ramp to each divided floor area being in immediate contact with said area whereby a car passing from said up ramp onto the divided floor area and running onto the down ramp will not intersect any line of ramp traffic.

2. A storage building having a receiving floor 70 and superimposed floors designated alternately full floors and intermediate floors, each of said intermediate floors being divided into two areas of lesser total area than the adjacent full floors, a plurality of up ramps extending upwards to 75

- communicate with the superimposed floors and a plurality of corresponding down ramps connecting the superimposed floors with the receiving floor, each of said ramps being arranged to 5 serve one only of the divided two areas of the intermediate floors the last mentioned up and down ramp to each divided floor area being in immediate contact with said area whereby a car passing from said up ramp onto the divided floor 10 area and running onto the down ramp will not intersect any line of ramp traffic, the headroom height of all of said ramps being substantially equal to the headroom height between adjacent full floors.
- 15 3. A storage building having a receiving floor, superimposed floors designated as full floors and intermediate floors, each of said intermediate floors being divided longitudinally of the building into two areas, said building having ramp connecting traffic aisles in the same general direction as the line of the line of division of the intermediate floors, a plurality of up ramps and corresponding down ramps arranged in side by side relation and extending transversely of the 20 line of division of the intermediate floors and at opposite ends of the traffic aisles, the up ramps at one end of said aisles being towards the centre of the building with the down ramps towards the outside of the building and the up ramps at the 25 other ends of the aisles being towards the outside of the building and the adjacent down ramps being between said up ramps and the centre of the building.
- 30 4. A storage building having a receiving floor, superimposed floors designated as full floors and intermediate floors, each of said intermediate floors being divided longitudinally of the building into two areas, said building having ramp connecting traffic aisles in the same general direction as the line of the line of division of the intermediate floors, a plurality of up ramps and corresponding down ramps arranged in side by side relation and extending transversely of the 35 line of division of the intermediate floors and at opposite ends of the traffic aisles, the up ramps 40
- 45 at one end of said aisles being towards the centre of the building with the down ramps towards the outside of the building and the up ramps at the other ends of the aisles being towards the outside of the building and the adjacent down ramps being between said up ramps and the centre of the building.
5. A storage building having a receiving floor 15 and superimposed floors, two pairs of ramps connecting adjacent floors and being spaced on opposite sides of an intervening storage area, each pair of ramps including an up ramp and a down ramp arranged that travel up and down is in the 20 same longitudinal direction, the up ramp of one pair being contiguous to an intervening storage area of a floor and the down ramp of the other pair being contiguous to the same intervening storage area, the down ramp of the first mentioned pair and the up ramp of the second mentioned pair being remote from the intervening storage area.
6. A storage building having a receiving floor 25 and superimposed floors, comprising full floors 30 and intermediate floors divided into spaced areas, said superimposed floors being encompassed by pairs of up and down ramps connected by traffic aisles, each of said divided intermediate floors being served at one end by an up ramp of one of the ramp pairs and at the other end with a down ramp of another ramp pair, said last mentioned up ramp and down ramp being in immediate contact with the intervening storage area whereby a car entering the storage 35 area from said up ramp and running onto said down ramp does not intersect any line of ramp traffic.

MONTAGUE MOORE. 45
